CLAIM

The ornamental design for a medication dispensing spool, as shown and described.

DESCRIPTION

FIG. 1 is a perspective view of a medication dispensing spool, showing our new design.

FIG. 2 is another perspective view thereof, the broken line showing of the medication strip being for illustrative purposes only and forming no part of the claimed design.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.
